ROTARY FINGER SCRUBBING MACHINE

Henry Singer, Honolulu, Territory of Hawaii

Application October 12, 1943, Serial No. 505,983

3 Claims. (Cl. 15—97)

1

This invention relates broadly to the class of toilet and pertains particularly to an improved mechanical device for effecting the cleansing of the fingers.

The principal object of the invention is to provide a device in which the finger may be placed to receive a thorough scrubbing or washing by the action of the device turning on and about the finger, the invention in its simplest form consisting of a cylindrical body of porous or whipped rubber having a tapered socket into which the finger is inserted, the cleansing action being effected by turning the body about the finger while a more complicated but still a relatively simple form of the invention comprises a series of such cylindrical bodies or a single one thereof designed to be rotated by hand or mechanical means for cleaning a number of fingers at one time.

A further object of the invention is to provide a finger cleansing device whereby there may be obtained a materially better cleansing action than it is possible to obtain by the use of the ordinary method of rubbing or brushing the fingers with a nail brush.

Another object of the invention is to provide a finger cleansing device employing a porous or whipped rubber socketed cylindrical body in which the finger is placed, which can be easily kept ready for immediate use by allowing the soap to remain in the pores of the body so that it is only necessary to wet the fingers and the rubber body and immediately proceed with the cleansing or scrubbing operation either by turning the body of the cylinder by hand or by the mechanical means provided for supporting and rotating the cylinder.

The invention will be best understood from a consideration of the following detailed description taken in association with the accompanying drawings, with the understanding that minor changes and modifications may be made in the structure so long as such changes do not depart from the spirit of the invention as expressed in the claims.

In the drawings—

Figure 1 is a view partly in longitudinal section and partly in elevation of the hand form of finger cleaner embodying the present invention.

Figure 2 is a transverse section taken on the line 2—2 of Figure 1.

Figure 3 is a view at top plan of mechanism operating finger cleaner employing unit similar to the unit shown in Figure 1.

Figure 4 is a view partly in vertical longitudinal section and partly in side elevation of the structure shown in Figure 3.

Figure 5 is a transverse section on the line 5—5 of Figure 4.

In accordance with the present invention there is provided a simplified form for hand use. This 60

2

form of the device comprises, as shown in Figure 1, a cylindrical body of sponge rubber, otherwise known as porous or whipped rubber, which may be about three or four inches long and which is provided with a longitudinally extending hole or socket 11 leading from one end for a distance of from two to three inches. This socket is slightly conical or tapered as shown, being finished off at its inner end in a rounded point 12.

10 The outer side of the cylinder is also tapered at the top or that end through which the socket 11 opens, as indicated at 13. This facilitates the placing of the body on the finger so that the inner end can be conveniently gotten between two adjacent fingers.

15 A convenient method of forming the body 10 is obviously to cast the same in a mold in one piece. In following this method it will then be necessary to remove the smooth or less porous outside skin which will be formed over the surface of the cylinder and around the wall of the socket 11 so that there will be no interference with the free passage of water through the pores of the body.

20 The manner of using this device will be readily apparent. The user after wetting the body thoroughly will drop a few granules of powdered soap or drops of liquid soap into the socket or cavity 11 and then insert the finger to its full length. The body will then be rotated as rapidly as possible about the finger so that there will be formed a lather and at the same time the rough surface of the wall of the socket will impart a thorough scrubbing to the finger.

25 In Figures 3 to 5 there is illustrated a mechanically operated form of the present finger cleaning device. In this mechanical construction there is provided a suitable housing base 14 through the length of which there extends a shaft 15 supported at its end in suitable bearings in the end walls of the housing and extending at both ends beyond the end walls of the housing to receive, upon each end, a hand crank 16. Within the housing there may be mounted an electric motor 17 having a suitable operative coupling 30 18 with the shaft 15 to effect the rotation of the latter, when the motor is energized.

35 Also within the base 14 there is supported a suitable tubular housing, through the length of which the shaft 15 passes, this housing being made fluid tight at its ends around the shaft so that it may be filled with a suitable lubricant.

40 Mounted upon the top of the base 14 is a block 20 formed of any suitable material such as hard rubber, synthetic resin or the like and this block is maintained in position by intergrooved pins 21 which is carried and which are designed to engage in suitable sockets, not specifically identified.

45 A wall 22 extends up from the block 20 at the edges thereof forming the chamber 23 and attached to one side of this wall is a suitable

3

cover such as a rubber sheet or the like, 24, which can be extended across the open top of the chamber 23 to cover the hands, as herein-after described.

Formed in an opening through the top of the block body 20 are five holes 25 each of which terminates at its bottom short of the bottom of the block 20. Extending upwardly into the bottom of the block 20 are five vertical shafts 26 each of which at its lower end is suitably rotatably supported in the wall of the tubular housing 19 and extends into the latter where it is connected with a bevel or miter gear 27 which is in toothed connection with a corresponding gear 28 secured to the shaft 15. At the upper end of each shaft 26 there are formed clutch lugs 29 and these couple with correspondingly formed clutch lugs 30 formed upon the lower end of the stem 31 which extends downwardly from the adjacent hole 25 with which the shaft 26 is aligned and which is integrally connected at its upper end with a cup 32, disposed in the lower part of the hole.

Each of the holes 25 has therein one of the rubber cleansers 33 which generally correspond in form and construction with the hand unit 19. The lower end of each cleanser extends into a cup 32 and may be secured therein by means of a transversely extending locking pin 34 whereby rotation of the finger cleanser is compelled when the attached shaft 26 is rotated.

In the use of this mechanically operated finger cleaner the user places his hand within the chamber or pan 23 with each finger extended into a central opening or socket of the rubber cleanser 33. The downward pressure imparted to the cleansers by the insertion of the fingers thereinto keeps the clutching members 29 and 30 of the shafts 26-31 coupled together and it will thus be seen that when the hand is lifted this clutching engagement will be broken due to the fact that such lifting will move the rubber cleansers upwardly and will likewise shift the stem 31 away from the adjacent shafts 26.

While the fingers are disposed within the rubber cleansers a rotary motion may be given thereto by turning the shaft 15 and the shaft 26 with which it is coupled, either by the use of the crank or by the operation of the electric motor 17.

The rubber cleansers will, of course, be soaked with water and soap and consequently some splashing of the soapy solution will occur. By turning the sheet 24 over to cover the top of the chamber 23 the user will be protected against the soapy solution splashing from the chamber or pan. After the device has been used the entire block 20 can be lifted from the base 14 and placed under a faucet so as to wash out the holes as well as the cylindrical finger cleansers located therein.

From the foregoing it will be seen that the invention herein disclosed provides a simple, novel and effective means of cleansing the fingers, and that the device in its simplest form may be made of such size as to be readily transported so that it can be carried upon trips and used in hotels or other places, as well as at home. The construction of the form of the invention which is designed to be operated mechanically, is such that the device may be readily taken apart for cleaning and reassembled without difficulty and without requiring mechanical knowledge upon the part of the user.

I claim:

1. A device of the character stated, comprising a housing having a shaft extending there-

through, the housing having a top, a body seated upon the top of the housing over the shaft, said body having a series of upwardly opening sockets formed therein, a plurality of shafts extending vertically from and having operative connection with the first shaft, each of said shafts being aligned with the axial center of a socket, a stub shaft extending through the lower part of said body from within a socket, a separable coupling between each stub shaft and an underlying shaft, a relatively long socketed finger receiving member disposed in each of said sockets, and a connection between each of said members and the stub shaft extending into the socket in which the member is located, said socketed members being formed of suitable material to have a scrubbing effect upon a finger inserted thereinto, and means for rotating the first shaft to effect simultaneous rotation of the plurality of shafts and the stub shafts connected therewith.

2. A cleaning device of the character stated comprising a housing having an open top defined by an inturned flange, a shaft rotatably supported in and extending horizontally through the housing, a body supported upon the top of the housing on said flange and covering the open top of the housing, said body having a plurality of upwardly opening sockets, means detachably maintaining the body in position upon the top of the housing, a stub shaft extending downwardly from within each socket through the lower part of the body and into the housing, a vertically extending shaft disposed beneath each stub shaft and extending upwardly towards the same and having driving connection with the first shaft, a clutch member connecting each stub shaft with the adjacent end of the underlying upwardly extending shaft, said clutch members being separated as a unit upon lifting the body from the top of a housing, and a socketed finger receiving and cleaning element disposed in each of the said sockets and operatively coupled with the adjacent stub shaft, and means in the housing connected with the first mentioned shaft to rotate the same.

3. A cleaning device of the character stated in claim 1, in which the said body has its top cut out to form a basin into which said sockets open.

HENRY SINGER.
